UNITED STATES PATENT OFFICE.

BERTRAM G. COBB, OF INDEPENDENCE, KANSAS.

CHECK-PROTECTOR.

1,369,400.

Specification of Letters Patent. Patented Feb. 22, 1921.

Application filed February 21, 1918. Serial No. 218,501.

To all whom it may concern:

Be it known that I, BERTRAM G. COBB, a citizen of the United States, residing at Independence, in the county of Montgomery and the State of Kansas, have invented a new and useful Improvement in Check-Protectors, of which the following is the specification.

My invention relates to improvements in check protectors in which a metal, or other composition, cutter is used in connection with a specially printed check; and the object of my improvement is to furnish check users with a simpler and more effective means of protecting their checks against being raised to a higher denomination than that for which they were originally drawn.

I attain this object by the mechanism and the printed check illustrated in the accompanying drawing in which—

Figure 1 is a perspective view of the cutter, Fig. 2 is a view of the printed check and Fig. 3 is a view of the cutter in place on the check pad with a check in place for protecting.

Similar letters refer to similar parts throughout the several views.

The cutter or marker as shown by Fig. 1 is composed of thin metal or other composition and is formed so as to have a base *a*, and a relatively narrow L-shaped tongue or lug *b*, of suitable size to fit over the end of the pad of checks as shown in Fig. 3. The free end of the lug is pointed as shown at *b*. This part being not more than three quarters of an inch long so as not to interfere with turning back the check stubs.

Along the top of the check, Fig. 2, is a series of figures representing amounts of money to be used as maximum amounts which are to be indicated by the cutter as corresponding with the amounts written in the body of the checks. The series of fig-

ures may be varied and the line of printed information below the figures may be changed, but the arrangement must be preserved so as to coöperate with the action of the cutter.

The process of protecting a check consists of inserting the scheduled edge of check under the point of the cutter as shown in Fig. 3, pressing the point of the cutter down with the thumb and then tearing out a triangular piece from the edge of the check opposite the smallest amount as indicated by the information line printed just under the series of figures.

I am aware that prior to my invention check protectors have been made which require the use of a metal or other cutter for the purpose of facilitating the tearing off of certain portions of the check or stub, thereof. I therefore do not claim such a combination broadly, but I claim:

1. The combination with a check book of a check cutter including a base plate having a relatively narrow substantially L-shaped tongue secured at the end of one arm to said plate with its other arm overlying said plate and provided at its free end with a pointed check cutting element, said plate and tongue embracing the bound portion of the stubs of the check book whereby said stubs constitute a support for and maintain a detached check in engagement with the cutting element.

2. A device of the class described, comprising a flat elongated plate having an integral tongue carried by one longitudinal edge midway its length, said tongue extending at right angles from said edge and then extending forwardly over said plate in a plane parallel therewith, the free end of said tongue projecting forwardly and being pointed to form a check cutting element.
